UNITED STATES PATENT OFFICE

JOHN W. LAWSON, OF ANDERSON, INDIANA, ASSIGNOR TO DELCO-REMY CORPORATION, OF DAYTON, OHIO, A CORPORATION OF DELAWARE

ENGINE-STARTING APPARATUS

Application filed February 17, 1928. Serial No. 255,125.

This invention relates to apparatus for starting internal combustion engines and particularly to the type of engine starting apparatus in which a motor driven pinion is moved manually into mesh with a gear connected with an engine to be started and in which the pinion is automatically demeshed from the engine gear when the engine becomes self-operative regardless of whether the operator fails to release an actuating member which controls the movement of the pinion into mesh with the gear and causes the motor to operate.

In one of its aspects the present invention constitutes improvements in an engine starting apparatus disclosed in the copending application of John B. Dyer, Serial No. 245,300 filed January 11, 1928. The Dyer application discloses an engine starting apparatus in which the pinion is helically splined to a motor driven shaft so that it is capable of being automatically demeshed from the engine gear, and in which the pinion is moved manually into mesh with the engine gear before the motor switch is closed. In case of gear tooth abutment, the pinion is manually rotated so that it will be brought into meshing registration with the engine gear and then meshed with the engine gear before the motor switch is closed. The manually operated mechanism is so constructed and arranged that the part which directly pushes the pinion into mesh with the gear and rotates it in case of gear tooth abutment, will be automatically retracted from the pinion before the engine becomes self-operative so that there will be no hindrance to the demeshing of the pinion although the operator should fail to release the controlling member of the starting apparatus. It sometimes happens that the abutting end faces of the pinion and gear teeth become interlocked due to roughening of these abutting end faces which may be present for various reasons. Under these circumstances it occasionally happens that the pinion cannot be turned relative to the engine gear in order to move it in meshing registration without turning the engine gear slightly so that the interlocking condition can be relieved. To force the

engine gear to rotate by the operation of the manually operated mechanism for rotating the pinion subjects the pinion shifting mechanism to abnormal strains. Therefore the present invention provides a means for rotating the splined shaft upon which the pinion is mounted into a new initial position, said means being operated in response to the releasing of the actuator of the pinion shifting so that it may turn to normal position before attempting to repeat the pinion meshing operation.

Further objects and advantages of the present invention will be apparent from the following description, reference being had to the accompanying drawings, wherein a preferred form of embodiment of the present invention is clearly shown.

In the drawings:

Fig. 1 is a fragmentary longitudinal sectional view of the starting apparatus embodying the present invention.

Fig. 2 is a fragmentary sectional view on the line 2-2 of Fig. 1.

Fig. 3 is a perspective view showing the pinion actuating sleeve and a plunger co-operating therewith tending to hinder rotation of the sleeve under certain conditions.

Fig. 4 is a fragmentary sectional view taken on the planes of the axes *a-b* and *c-d* of Fig. 3 and looking in the direction of arrow 4 of Fig. 3.

Fig. 5 is a view on the line 5-5 of Fig. 4.

Fig. 6 is a view looking in the direction of the arrow 6 of Fig. 4.

Fig. 7 is a diagrammatic side view of the engine starting apparatus showing parts thereof in operative positions before the pinion is manually rotated into meshing registration with the engine gear.

Fig. 8 is a view similar to Fig. 7, but showing the apparatus when the pinion has been meshed with the engine gear and before the motor switch is closed.

Fig. 9 is a diagrammatic view showing the parts of the mechanism before actuator has been released and after the engine has become self-operative.

Figs. 10 and 11 are mechanical diagrams showing the operation of mechanism for

manually turning the motor driven shaft into a new position before repeating the starting operation in case of a jam between a pinion and engine gear.

5 In the drawings, 20, designates a supporting bracket or gear housing member by which the starting apparatus is attached to the frame of an engine not shown. The frame 20 supports a bearing 21 for an armature shaft 22 which is rotatable within a field frame 23 attached to the housing 20 and is journaled at its left end not shown within a bearing provided by the field frame. The shaft 22 is provided with helical splines 24 10 along which an internally helically splined pinion 25 is movable endwise in a helical path toward an engine gear 26 and into mesh with said gear due to the operation of a manually operated mechanism to be described. Motion 15 of the pinion 25 toward the right in Fig. 1 is arrested by its engagement with a stop member provided by a wire split ring 27 occupying a groove 28 in the shaft 22. End thrust of the shaft toward the right is transmitted to the housing 20 by thrust washer 29.

20 The manually or pedally operated mechanism for manually causing the pinion 25 to mesh with the gear 26 and then to cause the motor to turn the shaft 22 comprises a tubular sleeve 30 which is attached to and is maintained concentric with a hub 31, slideable along the shaft 22, by means of annular discs 32 and 33, the latter having an annular row of clutch teeth 34 adapted to cooperate with clutch teeth 35 provided by the left end faces of the teeth of the pinion 25. Obviously, if the sleeve 30 is moved endwise along the shaft, the pinion 25 will be pushed against the gear 26 and the clutch teeth 34 and 35 will 25 be rotated so that the pinion may be rotated by rotating the sleeve 30 when necessary to move the pinion into meshing registration with the gear after it has engaged the latter. The mechanism for moving the sleeve 30 toward the right in Fig. 1 and for rotating the same under the conditions mentioned comprises a pin or stud 36 which is movable longitudinally of the sleeve 30 and is received by an oblique slot 37 formed therein. The pin 30 is mounted on the lower arm of a lever 38 which is pivotally supported on a screw or bolt 39 attached to the gear housing 20. The upper arm of the lever 38 is connected with a pedal rod 40 which slides through the floor-board 41 of the vehicle. The pedal 40 and lever 38 are normally maintained in the position shown in Fig. 1 by a spring 42 which is expandible or contractable within a recess 43 provided by the housing 20 and which urges 45 a plunger 44 against the lever 38. The spring 42 operates also to apply a brake to the armature 22 so that motion may be quickly arrested after a starting operation has been performed so that the starting operation may be 50 repeated as promptly as possible in case of

55 a false start, meaning a condition wherein the engine has operated only long enough to demesh the pinion from its gear but does not remain self-operative. The brake referred to includes a brake disc 50 which is attached to the shaft 22, a floating brake disc 51, a floating brake disc 52, and the annular disc 32. Obviously the spring 42 in urging the disc 32 toward the disc 50, will force the disc 51 against the disc 50. The braking effect is 60 produced by causing the disc 51 to remain stationary due to the engagement of a lug 53 extending from the disc 51 with a plate 54 which is attached to the housing 20 by a screw 55 and is prevented from rotating about the screw 55 by providing the plate 54 with a lug 56 extending into a hole 57 provided in the housing 20.

65 In order to prevent the turning of the sleeve 20 by the movement of the pin 36 toward the right of Fig. 1 until it is necessary to turn the sleeve 30 in order to turn the pinion into meshing registration with the engine gear, the sleeve 30 is shaped as shown in Figs. 3 to 6 inclusive so as to provide surfaces 60 and 61 at different distances from the axis of the sleeve and connected by a ledge or shoulder 62 which normally is engaged by spring pressed plunger 63 guided by recess 64 in the frame 20 and urged by a spring 65 toward the sleeve 30. A screw plug 66 retains the spring 65 within the recess 64. Since this feature is not my invention but is described and claimed in the copending application of John B. Dyer referred to, this feature will be described here very briefly. The normal position of the plunger is at 63^a in Fig. 5. When the sleeve 30 has been moved endwise a distance represented by line b—a which distance is sufficient to cause the pinion to touch the engine gear as shown in Fig. 7, the position of the plunger 63 relative to the sleeve 30 will be as indicated at 63^b in Fig. 5. During the rotation of the sleeve 30 by the operation of lever 38 in a counter-clockwise direction in order to move the pinion into meshing registration with the engine gear, the sleeve moves relative to the plunger the distance represented by the line c—b in Fig. 5 and the position of the plunger 63 relative to the sleeve at the instant of gear meshing is indicated at 63^c in Fig. 5. During the movement of the sleeve 30 toward the right in Fig. 1 in order to move the pinion into mesh with the engine gear as shown in Fig. 8, the relative movement between the plunger and sleeve will be represented by line d—c and the position of the plunger relative to the sleeve just before cranking the engine will be as indicated at 63^d in Fig. 5. During the cranking of the engine, the sleeve 30 will move relatively to the plunger 63 in a helical path as indicated by the line e—d and the position of the plunger 63 relative to the sleeve 30 before the engine becomes 70 75 80 85 90 95 100 105 110 115 120 125 130

self-operative will be indicated at 63^a. This position of the sleeve 30 is shown in Fig. 9, and it will be understood that the sleeve 30 moves in an oblique or helical path due to the coaction between the side of the slot 37 and the pin 36 which then remains stationary. Fig. 9 shows the condition of the apparatus after the engine has become self-operative and before the operator has released the actuating pedal. It is therefore apparent that before the engine starts the sleeve will have been moved clear of the pinion so that the pinion may be demeshed without striking the sleeve. As explained more fully in the Dyer application referred to the sleeve 30 is provided with a projection 70 which is so located relative to the plunger 63 when in the relative position 63^a that it is necessary for the operator to release the pedal 40 in order to permit the plunger 63 to return to the relative position 63^a before a starting operation can be performed.

While Fig. 5 indicates movement of the plunger 63 relative to the sleeve 30 into five different positions it will be understood that in fact the sleeve moves relative to the plunger. When the actuating pedal is released, the sleeve 30 will be rotated as represented by line a—e in Fig. 5 due to the coaction of the pin 36 and side of the slot 37, in a counterclockwise direction as viewed in Fig. 2. During this return rotation of the sleeve 30 the floating brake member 51 is not held from rotating but moves away from the stop 53, so that the spring 42 is not hindered from restoring the lever 38 by the full braking effect applied to stop rotation of the motor shaft 22. The only frictional resistance to the return rotation of sleeve 30 is that present between its hub 31 and the shaft and that between its end disc 32 and the disc 52. On the other hand, when braking rotation of the shaft 22, which rotates clockwise as viewed in Fig. 2, the disc 51 is held stationary, so that both sides of it operate as braking surfaces.

Assume that when the pinion 25 has been moved into the position shown in Fig. 7, the pinion cannot be easily rotated relative to the gear 26 in order to mesh the pinion with the gear, due to roughening the end faces of the abutting teeth. When these conditions arise, the operator will release the pedal 40 to permit the lever 38 to return to normal position. In doing so, the lever 38 moves a pawl 80 pivoted thereon at 81 from a position shown in Fig. 10 to that shown in Fig. 11. The point 82 of the pawl 80 engages a ratchet 83 provided by the disc 50 and thus rotates the shaft 22 to a position differing from that previously occupied by an angular distance such that, when the pinion meshing operation is repeated the pinion can be readily meshed with this engine gear.

Counterclockwise rotation of the pawl 80

relative to the lever 38 is limited by providing the lever with a stop 84 for receiving a lug 85 of the pawl 80. Hence the pawl 80 occupies the position shown in Fig. 8 during the engine cranking operation, and the position shown in Fig. 9 after the engine becomes self-operative and before the pedal is released.

In order that the pawl 80 will not be engaged by the ratchet 83 except when needed, the pawl carries a lug 86 engageable with a plane part of the disc 50, as shown in Fig. 1.

The motor is controlled by a switch enclosed by a case 90 attached to the motor frame and operated by a plunger 91 which moves toward the motor frame into switch closing position, and which is moved by a spring 92 away from the motor frame into switch open position. The plunger 91 is located in the path of movement of a stud 93 attached to the lever 38, and normally spaced from the plunger 91 at a distance such that the switch will not be closed until after the pinion 25 has been nearly fully meshed with the gear 26 as shown in Fig. 8. After the switch is closed the operation of the motor will move the pinion against the stop ring 28, this position of the pinion being indicated by dash-and-dot lines 25^a in Fig. 8.

While the form of embodiment of the present invention as herein disclosed, constitutes a preferred form, it is to be understood that other forms might be adopted, all coming within the scope of the claims which follow.

What is claimed is as follows:

1. Engine starting apparatus comprising in combination, a motor, a shaft driven by the motor, means for connecting the shaft with an engine to be started and including a pinion connected with the shaft and movable into mesh with an engine gear and provisions whereby the pinion will be automatically demeshed from the gear when the engine starts, manually operated means for moving the pinion into mesh with the gear and having provisions for rotating the pinion while it is pressed against the gear, and means operable upon the release of the manually operable means for rotating the shaft.

2. Engine starting apparatus comprising, in combination, a motor, a helically splined shaft driven by the motor, a pinion connected with the splines and slidably along the shaft into mesh with an engine gear, an actuating member, a device operated by said member for moving the pinion into mesh with the gear and having provisions for rotating the pinion while it is pressed against the gear, means for returning the actuating member to normal position, and means actuated by the return movement of the actuating member for rotating the shaft.

3. Engine starting apparatus comprising, in combination, a motor, pinion operated by

the motor and movable into mesh with the gear of an engine to be started, a member for moving the pinion, a spring for returning the member to normal position, a ratchet carried by the shaft of the motor, and pawl operated by the member for engaging the ratchet in order to turn the shaft when the member is returning to normal position.

4. Engine starting apparatus comprising, in combination, a motor, a shaft driven by the motor, means for connecting the shaft with an engine to be started and including a pinion connected with the shaft and movable into mesh with an engine gear and provisions whereby the pinion will be automatically demeshed from the gear when the engine starts, manually operated means for moving the pinion into mesh with the gear and having provisions for rotating the pinion while it is pressed against the gear, said provisions including a sleeve movable along said shaft and a manually operated member movable longitudinally of the shaft and received by an oblique surface provided by the sleeve, and means for braking rotation of the shaft and including a brake surface connected with the shaft, a brake surface connected with the sleeve, a brake member floating between said brake surfaces, means for moving the manually operated member so as to cause the brake surfaces to engage the floating brake member through movement of the sleeve away from the pinion and to cause the sleeve to rotate to normal position in a direction opposite to the direction of rotation of the shaft, and a stationary stop limiting rotation of the floating brake member only in the direction of rotation of the shaft.

5. Engine starting apparatus comprising, in combination, a motor; a shaft driven by the motor; means for connecting the shaft with the gear of an engine to be started including a pinion engageable with the gear, and provisions whereby the pinion may be automatically demeshed from the gear when the engine becomes self-operative; a driven clutch connected with the pinion; a driving clutch endwise movable into operative engagement with the driven clutch; a manually operable member for controlling the motor; a device operated by the manually operable member for moving the driving clutch axially and rotatively in order to move the driving clutch into engagement with the driven clutch and the pinion into mesh with the engine gear and to rotate the pinion prior to meshing in case the pinion abuts the gear teeth; and means operable upon release of the manually operable member for rotating the shaft.

6. An engine starter comprising, in combination, a motor; a manually operable member for controlling the motor; a shaft driven by the motor; means for connecting the shaft with the gear of an engine to be started and

including a pinion slideable along the shaft into mesh with the engine gear, and provisions whereby the pinion will be automatically demeshed from the engine gear when the engine starts; a driven clutch member connected with the pinion, a driving clutch member freely rotatable on the shaft and axially movable into engagement with the driven clutch; a device operated by the manually operable member for moving the clutch members axially in order to move the pinion into mesh with the gear, and for rotating the clutch members in case the pinion abuts the gear prior to meshing therewith; and means operable upon release of the manually operable member for rotating the shaft.

7. An engine starter comprising, in combination, a motor; a manually operable member for controlling the motor; a shaft driven by the motor; means for connecting the shaft with the gear of an engine to be started and including a pinion slideable along the shaft into mesh with the engine gear, and provisions whereby the pinion will be automatically demeshed from the engine gear when the engine starts; a driven clutch member connected with the pinion, a driving clutch member freely rotatable on the shaft and axially movable into engagement with the driven clutch; a device operated by the manually operable member for moving the clutch members axially in order to move the pinion into mesh with the gear, and for rotating the clutch members in case the pinion abuts the gear prior to meshing therewith; means resiliently tending to prevent rotation of the clutch by the manually operable member, while permitting endwise movement of the clutch to move the pinion into engagement with the engine gear; and means operable upon release of the manually operable member for rotating the shaft.

8. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; manually operable means for shifting the pinion endwise into mesh with the engine gear and for rotating the pinion in case the pinion teeth collide with the engine gear teeth, said means including two members movable along the shaft, one of said members being rotatable, and one of said members having a part located oblique to the direction of bodily motion of said members and engaged by the other member whereby the rotatable, manually operable member may be rotated by the other member when moved along the shaft, and means for connecting the rotatable member with the pinion; and means operable upon

release of the manually operable means for rotating the shaft.

9. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; a device for shifting the pinion endwise into mesh with the engine gear and for rotating the pinion in case the pinion teeth collide with the engine gear teeth, said device including two members movable longitudinally of the shaft, said members having an oblique slot and pin connection with each other for movement together longitudinally of the shaft, and for angular movement one relative to the other when longitudinal movement of one of the members is obstructed, said member being adapted to shift the pinion longitudinally and to rotate the pinion; manually operable means for actuating said device; and means operable upon release of the manually operable means for rotating the shaft.

10. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; a device for shifting the pinion endwise into mesh with the engine gear and for rotating the pinion in case the pinion teeth collide with the engine gear teeth, said device including a sleeve movable along the shaft and provided with a slot oblique to the shaft, and a pin movable longitudinally of the shaft and engaging the slot, whereby the pin and sleeve may move together to move the pinion into mesh with the engine gear and whereby the sleeve may be rotated in case movement thereof is obstructed, said sleeve and pinion having clutching means for imparting rotation to the pinion; a manually operable member for actuating said pin; and means operable upon release of the manually operable member for rotating the shaft.

11. Engine starting apparatus comprising, in combination, a motor; a motor switch mounted upon the motor field frame; a housing extending from one end of the motor frame; a shaft driven by the motor and supported by the motor frame and housing and provided with a spirally splined portion; a pinion directly connected with said splined portion of the shaft; a lever pivoted on the housing and adapted to operate the motor switch and having an arm extending within the housing and carrying a pin movable longi-

tudinally of the shaft; a sleeve movable along the shaft and having an oblique slot receiving the pin; and axially engageable clutching means provided by the sleeve and pinion whereby the pinion will be rotated in case the pinion teeth abut the engine gear; and means operable upon the release of the lever for rotating the shaft.

12. Engine starting apparatus comprising, in combination, a motor; a motor switch mounted upon the motor field frame; a housing extending from one end of the motor frame; a shaft driven by the motor and supported by the motor frame and housing and provided with a spirally splined portion; a pinion directly connected with said splined portion of the shaft, axially engageable driving and driven clutch members, the driven member being provided by the pinion; a device for causing the clutch members to engage and to move the pinion endwise into mesh with the engine gear and for rotating the clutch members in case the pinion teeth abut the engine gear teeth; manually operable means for causing said device to mesh the pinion with the gear and then for causing the switch to be closed; means responsive to the operation of the motor while cranking the engine for causing the driving clutch member to be retracted from the driven clutch member; and means operable upon the release of the manually operable means for rotating the shaft.

13. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; a device for shifting the pinion endwise into mesh with the engine gear and for rotating the pinion in case the pinion teeth collide with the engine gear teeth, said device including a sleeve movable along the shaft and provided with a slot oblique to the shaft, and a pin movable longitudinally of the shaft and engaging the slot, whereby the pin and sleeve may move together to move the pinion into mesh with the engine gear and whereby the sleeve may be rotated in case movement thereof is obstructed, said sleeve and pinion having clutching means for imparting rotation to the pinion; a manually operable member for actuating said pin; and means operable upon release of the manually operable member for rotating the shaft.

14. Engine starting apparatus comprising, in combination, a motor; a shaft operated by the motor; means connecting the shaft with

- the gear of an engine to be started and including a pinion mounted on the shaft for longitudinal movement thereof and rotary movement therewith and provisions whereby the pinion will be automatically demeshed from the engine gear when the engine starts; a device for shifting the pinion endwise into mesh with the engine gear and for rotating the pinion in case the pinion teeth collide with the engine gear teeth, said device including a sleeve movable along the shaft and provided with a slot oblique to the shaft, and a pin movable longitudinally of the shaft and engaging the slot, whereby the pin and sleeve may move together to move the pinion into mesh with the engine gear and whereby the sleeve may be rotated in case movement thereof is obstructed, said sleeve and pinion having clutching means for imparting rotation to the pinion; manually operable means for actuating said device; cooperating axially engageable brake members connected respectively with the shaft and with the sleeve, and a spring for returning the sleeve to normal or non-operating position and for causing the brake members to be engaged whereby motion of the shaft may be quickly arrested; and means operated by said spring for rotating the shaft.
15. An engine starter drive comprising, in combination, a rotatable drive-connecting-member movable axially into driving relation with a rotatable part of the engine to be started; automatic means for disconnecting the drive-connecting-member from the engine part when the engine starts; a manually operable device for moving the drive-connecting-member into driving engagement with the engine part, said device including two members, one of which is rotatable coaxially of the drive-connecting-member, means for connecting the drive-connecting member with the rotatable, manually operable member, and means for connecting the manually operable members for endwise movement together, or so that endwise movement of one member relative to the other will effect rotation of the rotatable, manually operable member; and means effective upon the release of the manually operable device for effecting rotation of the drive-connecting-member.
16. An engine starter drive comprising, in combination, a rotatable drive-connecting-member movable axially into driving relation with a rotatable part of the engine to be started; automatic means for disconnecting the drive-connecting-member from the engine part when the engine starts; a manually operable device for moving the drive-connecting-member into driving engagement with the engine part, said device including a member rotatable coaxially of the drive-connecting-member and movable axially into engagement with the drive-connecting-member,

means for rotatively connecting said members, a manually operable part movable along the rotatable, manually operable member, and means for connecting the manually operable part and member so that they may move together and so that, in case axial movement of the rotatable manually operable member is arrested, further movement of the manually operable part will effect rotation of the manually operable member; and means responsive to the release of the manually operable member for effecting rotation of the drive-connecting-member.

17. An engine starter drive comprising, in combination, a rotatable drive-connecting-member movable axially into driving relation with a rotatable part of the engine to be started; automatic means for disconnecting the drive-connecting member from the engine part when the engine starts; a manually operable device for moving the drive-connecting-member into driving engagement with the engine part, said device including two elements adapted to move in the direction of movement of the drive-connecting-member when approaching the engine part, one of said elements being rotatable coaxially of the drive-connecting-member and engageable with said member, means for rotatively connecting the rotatable element and the drive-connecting member, and means for connecting the elements so that, when the rotatable element is moved axially by the other manually operable element, the rotatable element tends to rotate, and means tending to resist rotation of the rotatable, manually operable element; and means responsive to the release of the manually operable element for effecting rotation of the drive-connecting-member.

18. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; means for shifting the pinion endwise into mesh with the engine gear and for rotating the pinion in case the pinion teeth collide with the engine gear teeth, said means including a sleeve movable along the shaft and provided with slot oblique to the shaft, and a pin movable longitudinally of the shaft and engaging the slot, whereby the pin and sleeve may move together to move the pinion into mesh with the engine gear and whereby the sleeve may be rotated in case movement thereof is obstructed, said sleeve and pinion having clutching means for imparting rotation to the pinion; a frame adjacent the sleeve; means tending to resist rotation of the sleeve and comprising frictionally engageable parts one carried by the frame and the other con-

nected with the sleeve; and means effective upon the return of the pin to normal position for causing the shaft to rotate.

19. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; means for shifting the pinion endwise into mesh with the engine gear and for rotating the pinion in case the pinion teeth collide with the engine gear teeth, said means including a sleeve movable along the shaft and provided with slot oblique to the shaft, and a pin movable longitudinally of the shaft and engaging the slot, whereby the pin and sleeve may move together to move the pinion into mesh with the engine gear and whereby the sleeve may be rotated in case movement thereof is obstructed, said sleeve and pinion having clutching means for imparting rotation to the pinion; means tending frictionally to resist rotation of the sleeve during a substantial portion of the movement of the sleeve toward the pinion, said means being inoperative while the pinion is rotated by the sleeve in case of gear-tooth abutment; and means effective upon the return of the pins to normal position for causing the shaft to rotate.

20. An engine starter drive comprising, a rotatable driving member mounted to move axially into driving engagement with a member of the engine to be started; and manually operable means for moving the driving member axially, and for rotating it when necessary to effect its driving engagement with the engine member, said means including a rotatable engagement-producing member mounted for movement axially of the driving member, actuating means tending both to rotate and to move longitudinally the engagement-producing member, and frictional means including a non-rotatable part tending to resist rotation of the engagement-producing member; and means effective upon return of the actuating means to normal position for causing the driving member to rotate.

21. An engine starter drive comprising, a rotatable driving member mounted to move axially into driving engagement with a member of the engine to be started; manually operable means for moving the driving member axially, and for rotating it when necessary to effect its driving engagement with the engine member, said means including a rotatable engagement-producing member mounted for movement axially of the driving member, an actuator movable in the direction of axial movement of the engage-

ment-producing member, means for transmitting motion from the actuator to the engagement-producing member tending to move the latter rotarily and longitudinally, and frictional means including a non-rotatable part tending to resist rotation of the engagement-producing member; and means effective upon return of the actuator to normal position for causing the driving member to rotate.

22. An engine starter drive comprising, a rotatable driving member mounted to move axially into driving engagement with a member of the engine to be started; manually operated means for moving the driving member axially, and for rotating it when necessary to effect its driving engagement with the engine member, said means including a rotatable, engagement-producing member mounted for movement axially of the driving member and provided with a part oblique to its line of axial movement, an actuator engageable with said oblique part to tend both to rotate and to move axially the engagement-producing member, and a non-rotatable part engageable with the engagement-producing member to resist rotation thereof; and means effective upon the return of the actuator to normal position for causing the driving member to rotate.

23. An engine starter drive comprising, a rotatable driving member mounted to move axially into driving engagement with a member of the engine to be started; manually operable means for moving the driving member axially, and for rotating it when necessary to effect its driving engagement with the engine member, said means including, a tubular, rotatable, engagement-producing member mounted for movement axially of the driving member and provided with a slot oblique to its line of axial movement, an actuator pin engageable with said slot and movable substantially in the direction of axial movement of the driving member in order to tend both to rotate and to move axially the engagement-producing member, and a non-rotatable part engageable with the engagement-producing member to resist rotation thereof; and means effective upon the return of the pin to normal position for causing the driving member to rotate.

24. An engine starter drive comprising, a drive shaft; a pinion connected with and movable axially along the shaft into engagement with a gear connected with the engine to be started; manually operated means for moving the pinion along the shaft, and for rotating it when necessary, to effect driving engagement with the engine gear, said means including an engagement-producing member movable axially of the shaft into contact with the pinion and rotatable independently of the shaft, means rotatively connecting the

member and pinion, actuating means tending to rotate and axially move the member, and a non-rotatable part cooperating with the member to resist rotation thereof; and means effective upon the return movement of the actuating means to normal position for rotating the shaft.

25. An engine starter drive comprising, a drive shaft; a pinion connected with and movable axially along the shaft into engagement with a gear connected with the engine to be started; manually operated means for moving the pinion along the shaft, and for rotating it when necessary, to effect driving engagement with the engine gear, said means including a cylindrical engagement-producing member mounted to move along the shaft toward the pinion and having means clutching with the pinion to rotate the latter and having a part oblique to its line of axial movement, an actuator movable along the shaft for engaging the oblique part in order to tend both to rotate and to axially move the member, and a non-rotatable part cooperating with the member to resist rotation thereof; and means effective upon the return movement of the actuating means to normal position for rotating the shaft.

26. An engine starter drive comprising, a drive shaft; a pinion connected with and movable axially along the shaft into engagement with a gear connected with the engine to be started; manually operated means for moving the pinion along the shaft, and for rotating it when necessary, to effect driving engagement with the engine gear, said means including a tubular engagement-producing member mounted upon the shaft and movable axially into engagement with the pinion and having an annular row of clutch teeth engageable with the pinion teeth in order to rotate the pinion, said member having a slot oblique to the line of axial movement of the pinion, a pin movable along the shaft and received by the oblique slot whereby the pin tends to rotate and to axially move the member, and a stationary part cooperating with the member to resist rotation thereof, and means effective upon the return movement of the pin to normal position for rotating the shaft.

27. An engine starter drive comprising, a drive shaft; a pinion connected with and movable axially along the shaft into engagement with a gear connected with the engine to be started; manually operated means for moving the pinion along the shaft, and for rotating it when necessary, to effect driving engagement with the engine gear, said means including an engagement-producing member movable axially of the shaft into contact with the pinion and rotatable independently of the shaft, means rotatively connecting the member and pinion actuating means to rotate and axially move the member, a part

connected with the member and providing a longitudinal extending shoulder between surfaces located at different distances from the axis of the member, and a stationary plunger spring urged normally against the surface lying at the lesser distance from the axis of the member and engageable with said shoulder in order to tend to resist rotation of the member; and means responsive to the return movement of the manual means to normal position for causing the shaft to rotate.

28. An engine starter drive comprising, a driving shaft, a driving member connected with the shaft for rotary movement therewith and longitudinal movement thereof into driving engagement with a member of the engine to be started; and manually operated means for moving the driving member along the shaft, and for rotating it when necessary, to effect its driving engagement with the engine member, said means including an engagement-producing member movable along the shaft and rotatable independently thereof, an actuator movable alongside the shaft, means for transmitting motion from the actuator to the engagement-producing member tending to move the latter rotarily and longitudinally, a part connected with the member and providing a longitudinally extending shoulder between surfaces located at different distances from the axis of the member, and a stationary plunger spring urged normally against the surface lying at the lesser distance from the axis of the member and engageable with said shoulder in order to tend to resist rotation of the member; and means responsive to the return movement of the manual means to normal position for causing the shaft to rotate.

29. An engine starter drive comprising, a rotatable driving member mounted to move axially into driving engagement with a member of the engine to be started, and providing an axially engageable driven clutch element; a rotatable member providing a driving clutch element axially engageable with the driven clutch of the driving member; means for moving the driving clutch axially toward the driven clutch and for rotating the latter in case its axial movement is obstructed; and friction means including a fixed part tending to resist rotation of the driving clutch; and means responsive to the return movement of the clutch moving means to normal position for causing the driving member to rotate.

30. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically de-

meshed from the engine gear when the engine starts; manually operated means for moving the pinion axially and for rotating it, when necessary, to effect its engagement with the gear, said means including a rotatable; and axially movable engagement-producing member mounted upon the shaft, actuating means tending both to rotate and to axially move the member, and means including a non-rotatable part for frictionally resisting rotation of the member; and means operating during the return movement of the manual means to normal position for causing the shaft to rotate.

31. An engine starter drive comprising, a rotatable driving member mounted to move axially into driving engagement with a member of the engine to be started; an axially and rotarily movable engagement-producing member for moving the driving member axially, and rotatively when necessary, to effect its driving engagement with the engine driven member; an actuator movable along the engagement-producing member; means so connecting the actuator and engagement-producing member that movement of the actuator from normal position tends to rotate and to axially move the engagement-producing member, into coaction with the driving member, and rotation of the engagement-producing member in one direction while the actuator is relatively stationary causes axial movement of the engagement-producing member away from coaction with the driving member, and return of the actuator to normal position produces rotation of the engagement-producing member to normal position; a power operated rotatable element for turning the driving member and having frictional engagement with the engagement-producing member for turning the same in such direction that it will be axially retracted from coaction with the driving member; a device for resisting rotation of the engagement-producing member during a part of its movement from normal position into coaction with the driving member, said device being restored to operation by the return rotation of the engagement-producing member to normal position; and means for causing the driving member to rotate when the actuator returns to normal position.

32. An engine starter drive comprising, a drive shaft; a driving member connected with the shaft for rotary movement therewith and longitudinal movement thereof into driving engagement with a member of the engine to be started; an engagement-producing member journaled upon the shaft and movable axially into coaction with the driving member, and yieldably connected with the shaft so that rotation of the shaft tends to rotate it; an actuator movable along the shaft; means so connecting the actuator and engagement-producing member that

movement of the actuator from normal position tends to rotate and to axially move the engagement-producing member into coaction with the driving member, and rotation of the engagement-producing member by the shaft when operating the driving member while the actuator is relatively stationary causes axial retraction of the engagement-producing member from the driving member, and return of the actuator to normal position produces rotation of the engagement-producing member to normal position; a device for resisting rotation of the engagement-producing member during a part of its movement from normal position into coaction with the driving member, said device being restored to operation by the return rotation of the engagement-producing member to normal position; and means causing the shaft to rotate when the actuator returns to normal position.

33. An engine starter drive comprising, a rotatable driving member mounted to move axially into driving engagement with a member of the engine to be started; an axially and rotarily movable engagement-producing member for moving the driving member axially, and rotarily when necessary, to effect its driving engagement with the engine driven member; an actuator movable along the engagement-producing member; camming means connected with the engagement-producing member and coacting with the actuating member so that movement of the actuating member away from normal position tends to rotate and to axially move the engagement-producing member into coaction with the driving member; a device for resisting rotation of the engagement-producing member during a part of its axial movement into coaction with the driving member; camming means connected with the engagement-producing member and cooperating with the actuator for restoring the engagement-producing member to normal position and the rotation-resisting device to normal operation in response to the return of the actuating member to normal position; and means causing the driving member to rotate when the actuator returns to normal position.

In testimony whereof I hereto affix my signature.

JOHN W. LAWSON.
